JAMES MILLER SMITH, OF WENGLER, CALIFORNIA.

MITER-BOX AND SAW-GUIDE.

No. 810,175.

Specification of Letters Patent.

Patented Jan. 16, 1906.

Application filed August 2, 1905. Serial No. 272,823

To all whom it may concern:

Be it known that I, JAMES MILLER SMITH, residing at Wengler, in the county of Shasta and State of California, have invented certain new and useful Improvements in Miter-Boxes and Saw-Guides, of which the following is a specification.

My invention relates to certain new and useful improvements in miter-boxes and miter-box saw-guides in which means are provided for adjusting the saw at various angles to the horizontal and vertical planes, so as to cut any desired miter.

Again, my invention comprises a miter-box in which means are provided for adjusting the saw-guides up or down away from or toward the base of the box to enable the miter-boxes to be used on large or small work, as the case may be.

My invention has for its object to provide a miter-box and saw-guide of the foregoing character of a very simple and effective construction which can be easily and cheaply manufactured, which will readily serve its intended purposes, and which is capable of use with any kind of saw, either stiff-back or common saw or meat-saw.

With other objects in view than have been heretofore enumerated the invention also comprises certain novel construction, combination, and arrangement of parts, all of which will be first described in detail and then specifically pointed out in the appended claims, reference being had to the accompanying drawings, in which—

Figure 1 is a perspective view of my invention. Fig. 2 is a plan view thereof. Fig. 3 is a front elevation of the miter-box shown in Fig. 1. Fig. 4 is a vertical section taken on the line 4 4 of Fig. 2. Fig. 5 is a perspective view of the inside saw-engaging member. Fig. 6 is a cross-section on the line 6 6 of Fig. 7. Fig. 7 is a perspective view of the outside saw-engaging member. Fig. 8 is a cross-section on the line 8 8 of Fig. 5. Fig. 9 is a perspective view of the saw-engaging member connecting-bar. Fig. 10 is a detail perspective view of the saw-guide complete detached from the box.

Referring now to the accompanying drawings, in which like numerals and letters of reference indicate like parts in all of the figures, 1 designates the base, which is substantially triangular in shape for a purpose presently explained. Bolted or otherwise secured to the base 1 at its rear edge 1^a is a

block 2, forming a straight edge against which the timber or board to be cut is placed and to which the supporting-frame 3 of the saw-guide mechanism is secured. The frame 3 is formed of strap-iron 3^a, having a longitudinal slot 3^b running throughout its length and having its ends 3^c 3^d bent up at right angles to the base portion 3^a to form standards, as shown. The standards 3^c 3^d are slotted, as at 3^e, for a purpose presently understood.

The frame 3 is adjustably secured to the block 2 by the bolts 2^a 2^b, which pass through the base 1, the block 2, and the slot 3^b in the base portion 3^a of the frame 3 and are secured by thumb-nuts 2^b 2^b.

In practice the base 1 of the miter-box preferably has its rear edge 1^a about eighteen inches long, while the block 2 is about fourteen inches long by one and one-half inches high and one and one-half inches wide. The strap-iron 3 has its base portion 3^a about fifteen inches in length in practice, and its end standards 3^c 3^d are about four and one-half inches in height, the slot 3^b in the base 3^a being about three-eighths of an inch wide. The slot 3^e in the outer standard 3^c is preferably of less width than that of the inner standards 3^d for a purpose now to be explained.

4 designates a rod forming a part of the saw holder and guide, which projects through the slot 3^e of the standards 3^c 3^d and is secured to the standards by nuts 4^a 4^b on the threaded portions 4^c 4^d, respectively, of the rod, the diameter of the threaded portion 4^d being greater than that of the portion 4^c to avoid the necessity of threading the rod throughout its length, the portion 4^d coöperating with the standard 3^d, while the portion 4^c coöperates with the standard 3^c, as shown. The rod 4 at the inner end 4^e next the saw S is square in cross-section and provided with a vertical slot 4^g and a horizontal slot 4^h, for a purpose presently understood.

5 and 6 designate the saw-engaging members or guides proper which comprise the sheet-metal plates 5^a 6^a, whose upper and lower edges are bent over to form flanges 5^b 6^b to form the plates into a dovetail shape in cross-section to receive the dovetail portions 7^a 8^a of the blocks 7 and 8 of hard wood or other suitable material, each of which blocks 7 8 have their upper edges extended upwardly, as at 7^b 8^b, to form bearing portions for the rod of a stiff-back saw to ride on when such a saw is used. The plate 6^a has a pair of ears 6^c 6^d, stamped up out of the same in parallel

vertical planes spaced about six inches apart in practice, to which ears the horizontally-disposed semicircular scaled arcuate support 9 is pivotally secured by bolts 9^a 9^a, as shown. 5 The scaled arcuate support 9 passes through the slot 4ⁿ of the rod 4 and is secured by a thumb-screw 4^s, as shown, to permit adjustment of the saw-guides at different angles to the vertical. Midway the ends of the plate 10 6^a and at right angles to the ears 6^c 6^c the plate 6^a has a second pair of ears 6^d 6^d stamped therefrom, which ears 6^d 6^d lie in parallel horizontal planes in practice about three inches apart. A second semicircular scaled 15 arcuate support 10 is pivotally secured to the ears 6^d 6^d by bolts 10^a 10^a, as shown, to permit adjustment of the saw-guides at different angles to the horizontal. The scaled arcuate support 10 passes through the slot 4^s of the 20 rod 4 and is secured by a thumb-screw 4^t, as shown.

11 designates a yoke member having parallelly-arranged arms 11^a 11^a, one of which terminates in bifurcated portions 11^b 11^b, and 25 said parallel arms are bolted or riveted to plates 5^a 6^a, as shown. The screw member 11 serves to hold the plates 5^a 6^a in proper correlative position. The yoke member 11 is preferably formed of spring-steel, and the saw- 30 engaging members 5 and 6 are held the desired distance together by the adjustable bolt 12, which passes through the arms 11^a 11^a and is secured by the thumb-nuts 12^a, as shown.

35 In the drawings I have shown my invention as adapted for use as a "right-handed" miter-box, and by simply removing the frame 3 from the base 1 and turning it through an angle of one hundred and eighty degrees and 40 again securing it to the base 1 the apparatus becomes a "left-handed" miter-box.

In practice the braces 9 and 10 will be provided with suitable calibrations *x* and *y*, as shown, to enable the saw to be directly set in 45 the position desired by simply observing the reading of the calibrations on the braces 9 and 10.

50 My invention can also be used to saw wood of a greater size than will fit in the boxes by simply setting the box on the wood and clamping the frame 3 in a position drawn toward the end of the boxes until the saw is cleared of the base edge, when the desired cut can be readily made.

55 The apparatus can be used to cut a miter or bevel either with the work in the boxes or under the same. In framing heavy timbers the boxes can be set on the timber and worked in that manner. The rod 4 when slightly 60 loosened will readily turn to allow the guides 5 and 6 to adapt themselves to the movement of the saw when working out of the box, and particularly when saws such as two-handed wood-saws are used.

65 From the foregoing description, taken in

connection with the accompanying drawings, it is thought the complete construction, operation, and many advantages of my invention will be readily understood by those skilled in the art to which it appertains, and I desire 70 to say that many slight changes in the detailed construction and arrangement of parts can be made without departing from the spirit of the invention or the scope of the appended claims.

Having thus described my invention, what I claim, and desire to secure by Letters Patent, is—

1. An apparatus of the class described, comprising a base, a straight-edge block secured thereto, a supporting-frame adjustably secured to said block, a rod adjustably supported in said frame, and a saw-guide universally adjustably secured to said rod, substantially as shown and described. 80

2. In an apparatus of the class described, the combination with a base, and a straight-edge block secured thereto, of a supporting-frame adjustably secured to said block, a rod adjustably supported in said frame, and a 90 saw-guide adjustably secured to said rod.

3. In an apparatus of the class described, a base and a straight-edge block secured thereto, a supporting-frame adjustably secured to said block, a rod adjustably supported in said frame, a saw-guide comprising a pair of saw-engaging members, means for adjustably connecting said saw-engaging members together, and means for adjustably connecting one of said saw-engaging members to 100 said rod.

4. In an apparatus of the class described, a base, a straight-edge block secured thereto, a supporting-frame comprising a U-shaped member having a slotted base portion and 105 slotted standards at each end of said base portion, bolts passing through said straight-edge block and said base portion of the U-shaped supporting-frame to adjustably secure the frame to the block, a rod passing through the 110 slotted standards of said supporting-frame and adjustably secured thereto, a saw-guide comprising a pair of saw-engaging members each consisting of a sheet-metal plate, a block carried by each of said sheet-metal plates for 115 engaging the saw, a pair of semicircular guides disposed at right angles to each other and pivotally secured to one of said plates, said semicircular guides passing through apertures in said rod, and means for securing said guides to said rods in their various adjusted positions and means for securing said saw-engaging members together substantially as 120 shown and described.

5. In an apparatus of the class described, 125 a base, a straight-edge block secured thereto, a supporting-frame comprising a U-shaped member having a slotted base portion and slotted standards at each end of said base portion, bolts passing through said straight- 130

- edge block and said base portion of the U-shaped supporting-frame to adjustably secure the frame to the block, a rod passing through the slotted standards of said supporting-frame and adjustably secured thereto, a saw-guide comprising a pair of saw-engaging members each consisting of a sheet-metal plate, a block carried by each of said sheet-metal plates for engaging the saw, a pair of semicircular guides disposed at right angles to each other and pivotally secured to one of said plates, said semicircular guides passing through apertures in said rod, and means for securing said guides to said rods in their various adjusted positions and means for securing said saw-engaging members together, said last-named means comprising a bow-spring secured to said plates.
6. In an apparatus of the class described, a base, a straight-edge block secured thereto, a supporting-frame comprising a U-shaped member having a slotted base portion and slotted standards at each end of said base portion, bolts passing through said straight-edge block and said base portion of the U-shaped supporting-frame to adjustably secure the frame to the block, a rod passing through the slotted standards of said supporting-frame and adjustably secured thereto, a saw-guide comprising a pair of saw-engaging members each consisting of a sheet-metal plate, a block carried by each of said sheet-metal plates for engaging the saw, a pair of semicircular guides disposed at right angles to each other and pivotally secured to one of said plates, said semicircular guides passing through apertures in said rod, and means for securing said guides to said rods in their various adjusted positions and means for securing said saw-engaging members together, said last-named means comprising a bow-spring secured to said plates, and means for adjusting said saw-engaging members toward each other.
7. An apparatus of the class described, comprising a base, a straight-edge elongated block secured at the rear edge of said base, a supporting-frame consisting of an elongated slotted base portion secured to said elongated straight-edge block, bolts passing through said block and said slotted base portion of the supporting-frame for adjustably securing the same to the block, said supporting-frame also comprising slotted end standards, an elongated rod adjustably held in said slotted end standards, means on said rod for holding the same in position on said standards, said rod having one end provided with a vertical and a horizontal slot, a saw-guide consisting of a pair of sheet-metal plates dovetailed in cross-section, a pair of saw-engaging blocks having dovetailed portions held by said plates, a bow-spring secured to said plates to hold the saw-engaging members in position, an adjusting-bolt carried by said bow-spring for adjusting the saw-engaging members toward each other, one of said plates having a pair of ears stamped therefrom and arranged in parallel vertical planes, a semicircular arcuate member pivotally secured to said ears, and passing through the horizontal slot of the rod, said last-named plate having a pair of ears stamped therefrom and arranged in horizontal planes midway between the first-mentioned ears, a second semicircular arcuate member pivotally secured to said last-named ears and passing through the vertical slot of the rod and set-screws carried by said rod for coöperating with said semicircular arcuate members to lock them in their adjusted positions, said saw-engaging blocks having upwardly-extending edges for coöperating with the rib of a stiff-back saw to form guides therefor, all being arranged substantially as shown and described.

ing-bolt carried by said bow-spring for adjusting the saw-engaging members toward each other, one of said plates having a pair of ears stamped therefrom and arranged in parallel vertical planes, a semicircular arcuate member pivotally secured to said ears and passing through the horizontal slot of the rod, said last-named plate having a pair of ears stamped therefrom and arranged in horizontal planes midway between the first-mentioned ears, a second semicircular arcuate member pivotally secured to said last-named ears and passing through the vertical slot of the rod and set-screws carried by said rod for coöperating with said semicircular arcuate members to lock them in their adjusted positions all being arranged substantially as shown and described.

8. An apparatus of the class described, comprising a base, a straight-edge elongated block secured at the rear edge of said base, a supporting-frame consisting of an elongated slotted base portion secured to said elongated straight-edge block, bolts passing through said block and said slotted base portion of the supporting-frame for adjustably securing the same to the block, said supporting-frame also comprising slotted end standards, an elongated rod adjustably held in said slotted end standards, means on said rod for holding the same in position on said standards, said rod having one end provided with a vertical and a horizontal slot, a saw-guide consisting of a pair of sheet-metal plates dovetailed in cross-section, a pair of saw-engaging blocks having dovetailed portions held by said plates, a bow-spring secured to said plates to hold the saw-engaging members in position, an adjusting-bolt carried by said bow-spring for adjusting the saw-engaging members toward each other, one of said plates having a pair of ears stamped therefrom and arranged in parallel vertical planes, a semicircular arcuate member pivotally secured to said ears, and passing through the horizontal slot of the rod, said last-named plate having a pair of ears stamped therefrom and arranged in horizontal planes midway between the first-mentioned ears, a second semicircular arcuate member pivotally secured to said last-named ears and passing through the vertical slot of the rod and set-screws carried by said rod for coöperating with said semicircular arcuate members to lock them in their adjusted positions, said saw-engaging blocks having upwardly-extending edges for coöperating with the rib of a stiff-back saw to form guides therefor, all being arranged substantially as shown and described.

JAMES MILLER SMITH.
